United States Patent

Des. 242,322
Patented Nov. 16, 1976

242,322

LATCH

R. Arthur Miles, P.O. Box 333, Clio, Mich. 48420

Filed Aug. 22, 1975, Ser. No. 606,832

Term of patent 14 years

Int. Cl. D8—07

U.S. Cl. D8—131

FIG. 1

FIG. 3

FIG. 4

FIG. 2

FIG. 5

FIG. 1 is a perspective view of a design for a latch;
FIG. 2 is a front elevational view;
FIG. 3 is a top plan view; and
FIGS. 4 and 5 are left and right side elevational views
further illustrating the present invention.

I claim:

The ornamental design for a latch, as shown.
